CLAIM

I claim the ornamental design for a detachable bootie and garment, as shown and described.

DESCRIPTION

FIG. 1 is a front perspective view of a detachable bootie and garment showing my new design;

FIG. 2 is a front perspective view thereof showing the booties detached from the garment;

FIG. 3 is a rear perspective view thereof showing the booties attached to the garment; and,

FIG. 4 is a rear perspective view thereof showing the booties detached from the garment.
